APPARATUS FOR COUNTING PARTICLES

Hugh Alexander Dell and Emlyn Jones, Horley, England, assignors, by mesne assignments, to North American Philips Company, Inc., New York, N. Y., a corporation of Delaware

Application June 25, 1952, Serial No. 295,586

Claims priority, application Great Britain June 27, 1951

14 Claims. (Cl. 235—92)

The invention relates to apparatus for counting particles and is particularly but not exclusively concerned with the assessment of the dust content of an air sample.

Assessment of the contamination of air or other gas by dust has hitherto been effected by preparing a sample taken under controlled conditions, such sample being for example a transparent plate on which the dust particles have settled and been fixed, or an enlarged photograph of such a plate, visually examining the sample under a microscope and counting the particles in a representative area. This is a long and laborious task and the results obtained from the same sample by different observers may vary widely particularly when the particles vary greatly in size.

For certain purposes it is only necessary to have a total count of the number of particles in a given sample without size discrimination, and the object of the invention is to replace visual counting by automatic electrical counting apparatus giving such a total count.

If the particles in a given sample vary in size then there remains the difficulty, if some form of scanning of the sample is used, of ensuring that a large particle scanned more than once is only "seen" as a single particle so that a spurious count is avoided.

A further object of the invention is to remove this difficulty.

With these and other objects in view and according to the invention, particle counting apparatus comprises means such as a cathode ray tube for scanning a sample of the particles to be counted, pick-up means such as a photoelectric cell co-operating with the scanning means for producing an electrical signal which is a measure of the presence and distribution of the particles, means for avoiding multiple mounting of a large particle scanned more than once and counting means responsive to the derived signal or signals for giving an indication of the total number of particles scanned.

When the sample is in the form of a transparent plate bearing the particles or a photographic representation of the same to the same or a different scale the scanning means may comprise a cathode ray tube, the beam of which is caused, by suitable saw-tooth time bases, to trace out a raster of rectangular form and of such size as to illuminate the plate or such part of it as it is required to examine. By suitable optical means the light from the cathode ray tube face passing through the sample is caused to fall on a pick-up device such as a photo-cell so that the output of the pick-up device in time is an electrical representation of the presence or absence of particles in the scanning lines.

Since the particles may vary in size it is possible that a large particle may overlap two or more lines of scan and according to a further feature of the invention the sample scanning means provides effectively two scanning beams scanning adjacent lines, the pick-up means and associated amplifier or amplifiers and counting means being so arranged that when both beams encounter a particle the counting means is rendered inoperative and

2

is actuated when one only of said beams encounters a particle.

With such an arrangement three modes of utilising the signals provided by the pick-up means may be distinguished. In the first mode the signal derived from one beam is employed, for example after inversion, to cancel the signal derived from the other beam when both beams substantially simultaneously encounter a particle overlapping two or more lines of scan. Counting of such a particle or a small particle occupying only one scanning line may be effected either—

(a) By utilising the signal derived from one of the beams when it alone scans the particle so that counting is effected either when the particle is first encountered by one of the beams or when it is last encountered by the other beam, or

(b) By utilising the signals from both beams (when they are not present substantially simultaneously) so that a particle is counted when it is first encountered by one of the beams and when it is last encountered by the other beams, the total count thus obtained being divided by two.

In the second mode the electrical signals derived from the two beams may be of similar electrical polarity (for example positive going pulses) and are mixed so that when each beam only encounters a particle, a first type (or waveform) of signal is obtained whereas when both beams substantially simultaneously encounter a particle a different type (or waveform) of signal results. Such a different type of signal may be utilised to prevent actuation of the counter. In this case each particle will be counted twice as in the second of the regimes of the first mode so that the total count must be divided by two.

In the first mode the signal provided by one beam may be regarded as a counting signal and the signal provided by the other beam as a controlling signal whereby the transmission of the counting signal to the counter (when a particle is encountered) is prevented when the two signals are present substantially simultaneously but is permitted when the counting signal only is present. In this case counting may take place either when the particle is first encountered or when it is last encountered whichever is most desirable in a particular case.

Since large particles overlapping two or more scanning lines may present a leading edge which is not normal to the direction of line scan, it is possible to arrange that one of said beams, for example the leading beam in the direction of frame scan, which may be termed the guard beam, should encounter the leading edge of the particle in advance (in the direction of line scan) of the other beam (the trailing beam in the direction of frame scan) which may be called the scanning or counting beam so that the output from the pick-up due to the guard beam shall be operative to prevent actuation of the counter slightly before the scanning beam encounters the leading edge of the particle.

According to a further feature of the invention therefore the sample scanning means provides effectively two beams, namely a guard beam and a scanning beam, the guard beam being arranged effectively to scan along a line adjacent to the line scanned by the scanning beam and in advance of it in the direction of line scan by a predetermined distance.

The production of the two beams may be realised in several ways. In one form the known flying spot scanner of the cathode ray tube type may be employed in conjunction with means for repetitively deflecting the scanning spot in an appropriate direction and to the desired extent and at a suitable repetition frequency so that effectively two scanning beams are provided. In another form two flying spot light beams having distinguishably different optical properties and scanning adjacent lines may be used.

In accordance with a further feature of the invention

therefore, the sample scanning means comprises a flying spot scanner of the cathode ray tube type and spot wobbling means for repetitively deflecting the electron beam in an appropriate direction at a repetition frequency many times the line frequency whereby the single cathode ray beam provides effectively two scanning beams.

In accordance with yet another feature of the invention the sample scanning means provides a flying spot light beam and comprises beam dividing and differentiating means giving two scanning beams having distinguishably different optical properties, the pick-up means comprising two photo-electric devices each responsive to one only of said scanning beams. The flying spot light beam may be provided in the known manner by a flying spot scanner of the cathode ray tube type or by a light source and mirror drum or drums or equivalent optical elements and the beam may be divided by any suitable optical element or elements, the beam differentiating means, comprising colour filters or polarising means, the photo-electric devices being correspondingly colour or polarisation sensitive.

Other features of the invention will be apparent from the following description of several embodiments which are given by way of example only and with reference to the accompanying drawings in which:

Figure 1 is a representation of a portion of a particle sample;

Figure 2 is a block schematic diagram of a first form of particle counter;

Figure 3 is a circuit diagram of the switch unit of Figure 2;

Figure 4 is a block schematic diagram of a second form of particle counter;

Figure 5 is a block schematic of a third form of particle counter;

Figure 6 is a circuit diagram of the pulse selector switch and switch control and count pulse generator units of Figure 5;

Figure 7 shows typical waveforms of signals applied to the circuit of Figure 6;

Figure 8 is a block schematic diagram of a fourth form of particle counter;

Figure 9 is a circuit diagram of the differentiator and pulse selector, and coincidence switch units of Figure 8;

Figure 10 shows typical waveforms of signals applied to the circuit of Figure 9;

Figure 11 is a diagrammatic representation of one form of optical scanning system;

Figure 12 is a diagrammatic representation of a second form of optical scanning system;

Figure 13 is a diagrammatic representation of a scanning system utilising a modified scanning electron microscope.

In the following description of several practical embodiments of the invention and with reference to the operation of certain thermionic valves the phrase "open on the control (or suppressor) grid" means that the potential of the control (or suppressor) grid is such as to permit passage of the electron stream. By the phrase "cut-off on the control (or suppressor) grid" is meant that the flow of electron is substantially reduced or entirely prevented.

It is also to be understood that the size of the scanning spot at the sample under investigation is preferably not larger than the smallest particle it is desired to count and may be smaller, and the distance between the centres of the scanning lines comprising the raster is not less than the diameter of the scanning spot.

Referring now to the drawing, Figure 1 shows for the purpose of simplifying the following description a portion of a sample plate containing only a small particle 1 and a large particle 2. The actual sample may be a transparent plate having the particles adhering to it or it may be a photographic reproduction in the form of a lantern slide of an actual sample to the same or a different scale.

Alternatively the sample may be for example in the form of a photographic print from which light is reflected into the pick-up device and may be either a positive or negative image, that is to say the particles may appear as black marks on a white ground or as white marks on a black ground.

Apparatus for scanning such a sample and operating according to the first mode above mentioned is shown in one embodiment in Figure 2 in block schematic form. The scanning unit 3 comprises a flying spot scanner of the cathode ray tube type, having the usual saw-tooth line and frame time bases to cause the electron beam to produce a rectangular raster on the tube face. Associated with the cathode ray tube is a pick-up device 4 such as a photo-cell, the particle sample being interposed between the cathode ray tube face and the device 4 so that as the sample is scanned the photo-cell provides an electrical signal which is a representation of the presence or absence of particles in the scanning lines. These scanning lines are indicated in Figure 1 by the horizontal lines *a*, *b*, *c*, *d*.

With conventional single spot scanning and in the absence of size discriminating means the large particle will be scanned three times as the scanning beam traverses lines *a*, *b* and *c*, thus giving rise to two spurious signals.

In order to avoid this and to provide such size discrimination, a modification of the known "spot wobble" technique used in television may be employed as indicated in Figure 2. A unit 5 providing spot wobbling potentials is connected to the scanning unit 3 and is so arranged that the cathode ray beam is deflected in the direction of frame scan by a distance equal to one line width. In addition and for a purpose which will be hereinafter described the cathode ray beam is also deflected in the direction of line scan by a predetermined amount sufficient to ensure that the beam in its deflected position first scans the side of a particle sloping in the direction of line scan as shown at 6 in Figure 1. The repetition frequency at which the cathode ray beam is deflected is preferably many times the line frequency and in a practical example when the line frequency is 1000 c./s. the spot wobble repetition frequency may be for example 1 mc./s. The alternating potential giving rise to this deflection is preferably of square waveform.

For the purpose of the following description the cathode ray beam in its normal undeflected position will be called the scanning beam and in its deflected position the guard beam and the scanning will be assumed to be from left to right for line scan and top to bottom for frame scan with reference to Figure 1.

Referring again to Figure 2 the spot wobble unit 5 is connected to two input terminals of an electronic switch unit 7. The pick-up device is also connected to another input terminal of the switch unit and two output terminals of the unit are connected respectively to two inputs of an amplifier 8. These two inputs represent respectively the signals due to the scanning beam and guard beam and the amplifier is so arranged that when both signals are present one cancels the other thus effectively quenching the amplifier. The amplifier output is connected to a counter 9 of any suitable form.

A suitable circuit for the switch unit 7 is shown in Figure 3 and comprises two thermionic valves 10, 11, each having two control electrodes. These valves may be of the pentode type. The output of the photocell 4 is connected to the control grid 12 of valve 10 and to the control grid 13 of valve 11 and the spot wobbling square wave potential to the suppressor grid 14 of valve 10.

The same square wave potential inverted is supplied to the suppressor grid 15 of the valve 11. The output of valve 10 is supplied to the input of the amplifier and the output of the valve 11 to the amplifier quenching means.

In operation and assuming the scanning beam to be scanning line *a* in Figure 1 the output of the photocell

will, for example increase as the scanning spot traverses the particle but this increase will be discontinuous due to the repetitive deflection of the spot to the guard position. Valve 10 will, therefore, pass a series of pulses since grids 12 and 14 of the valve will go positive together but valve 11 will deliver no output since there is no output from the photocell in the "guard" position, although the inverted wave applied to the grid 15 of this valve tends to open the valve at the appropriate instant. The output from valve 10 is preferably integrated and supplied to the input of the amplifier as a single pulse, which after amplification and "squaring" is supplied to the counter.

As the scanning and guard beams approach the second, large particle, the photocell will deliver an interrupted output due to the guard beam since this encounters the particle before the scanning beam and this photocell output will only appear in the output circuit of valve 11, valve 10 remaining cut-off. When the scanning beam encounters the particle there will also be an output from valve 10 but by this time the output of the valve 11 will have reached a valve such that the output from valve 10 is quenched so that the counter is not energised. Therefore, on its first scan of the large particle (along line *a* Figure 1) the counter is inoperative and this applies also when line *b* is scanned since the guard beam encounters the particle in line *c*. On the next line, line *d*, however, the guard beam does not encounter the particle and the output from the photocell as the scanning beam scans line *c* causes operation of the counter in the same manner as with the small particle.

While the large particle is being scanned by both beams (for example lines *a* and *b*) the output of the photocell due to the guard beam may terminate before the output of the cell due to the scanning beam because of the shape or disposition of the particle. This is undesirable since it may give rise to a spurious count. It can be avoided by the provision of time delay means for example, in such a way that the amplifier remains quenched for a predetermined time after the termination of the control potential due to the guard beam.

In an alternative arrangement not illustrated, the outputs from valves 10 and 11 may be differentiated or otherwise converted in the known manner so that the output due to the scanning beam when it encounters the particle appears as a single pulse of short duration corresponding to the leading edge of the particle which pulse is supplied to the input of the amplifier as before. The single pulse due to the guard beam may be used, for example, to trigger a flip-flop circuit which returns to its stable state after a predetermined interval. The operation of the flip-flop circuit may be used to quench the amplifier and the time delay may be such as to ensure that the scanning beam pulse has had time to appear. In this case the time delay may be much shorter than in the previously described arrangement.

In the above described arrangements the guard beam scans the line preceding that scanned by the scanning beam (in the direction of frame scan) and in the case of a large particle the count only takes place after the particle has been fully scanned. The inverse arrangement may also be employed in which the guard beam scans the line succeeding the line scanned by the scanning beam (in the direction of frame scan). In this arrangement the particle is counted when it is first encountered by the scanning beam, subsequent encounters, in the case of a large particle, producing no actuation of the counter.

A second embodiment of the invention operating according to the second regime of the first mode is shown in block schematic form in Figure 4. In this arrangement the signal due to the main beam is taken to switch SM and the signal due to the guard beam is taken to a similar switch SG which switches are normally in the position shown in the drawing. Each switch is controlled by a signal fed into its associated switch control unit (i. e.

SM at H and SG at I). Outputs from these two switches are fed to a counter C capable of addition and subtraction. The arrangement will be more clearly understood from a consideration of the way in which it operates.

Considering the scanning of a large particle and assuming in this case that the scanning beam is in advance of the guard beam in the direction of frame scan, then, when the main beam encounters the particle, a signal is routed to the counter via the switch SM and the counter counts +1. Similarly whilst the signal lasts it is fed into the other switch control unit associated with switch SG at I and thus operates switch SG to its other position. On the first scan no signal due to the guard beam is offered and when the signal due to main beam ceases, switch SG reverts to the position shown in the drawing. On the next scanning line and while assuming that the main beam encounters the particle first, the arrangement works as on the first encounter so that +1 is added by the counter (making +2 in all) and switch SG is moved to its other position. The signal due to the guard beam now appears before the signal due to the main beam ceases and this guard beam signal is fed by the switch SG to the subtracting input of the counter which thus adds -1 (making +1 in all). This operation is repeated as long as both beams substantially simultaneously encounter the large particle until the scanning line is reached when only the guard beam gives a signal. This signal is routed to the switch control associated with switch SM at H and also to the counter which adds +1 (making +2 in all for the large particle).

In a similar way a small particle is counted twice so that the total count of the complete sample must be divided by two to arrive at the total number of particles.

It is to be noted that it does not matter whether the signal due to the main or guard beams appear first. Whichever it is adds +1 to the count and moves the other's switch over so that when the other signal appears it will add -1 and give the correct count.

A third embodiment of the invention operating according to the second mode above mentioned, will now be described with reference to Figure 5 in which, to avoid elaboration, the scanning beam dividing and pick-up means are indicated as unit 16. They may be similar to those described with reference to Figure 2 or as described hereinafter.

From the pick-up means two electrical signals are produced, one due to the scanning of a particle by the scanning beam and the other due to the guard beam as in the preceding embodiment.

In this embodiment however, each signal is of the same polarity and is differentiated in the known manner as indicated at 17 and 18 so that if for example the output of the photocell due to the scanning beam as it traverses a particle is a positive-going pulse of substantially rectangular form it is converted into a short positive going pulse (or spike) following by a negative going pulse (or spike). (See Figure 7a.) The two differentiated signals are added together and the resulting mixed pulses are supplied to the input of a switch unit 19 having outputs and to a pulse selector 20, the output of which goes to one input of a switch controller and count pulse generator unit 21. Two other inputs to the unit 21 are connected to the switch unit 19 and a further output from the unit 21 is taken to a counter 9 of any suitable form.

The operation of this arrangement will be more readily followed from a consideration of practical forms of the units 19, 20 and 21 which will now be described with reference to Figure 6. In this figure the switch unit

19 comprises two thermionic valves V₁, V₂ which are of the pentode type, the mixed signal above mentioned being supplied to the control grids of both valves. In the starting condition both valves are cut off on their control grids, the valve V₁ is also cut off on its suppressor grid and V₂ is open on its suppressor grid due to

7
the connection of these suppressor grids to the switch control and pulse generator unit 21.

This unit comprises a triode valve V_3 and a pentode valve V_4 which together form a bi-stable multivibrator, the anode of each valve being connected to the control grid of the other in the known manner. The suppressor grid of valve V_1 is connected to the anode of valve V_3 and the suppressor grid of valve V_2 is connected to the anode of valve V_4 . The anode of valve V_1 is connected to the control grid of valve V_4 with a time delay network R_1C_1 and the anode of valve V_2 is connected to the control grid of valve V_3 with a similar delay network R_2C_2 . In the starting condition the valve V_3 is conducting and valve V_4 is cut off on its control grid but is open on its suppressor grid.

If now a differentiated signal of the form shown in Figure 7(a) representing the scanning of a small particle by one of the beams is applied to the control grids of valves V_1 and V_2 , the valve V_2 conducts to its anode (since it is open on its suppressor grid) whilst valve V_1 remains cut off on its suppressor grid. A negative pulse is produced at the anode of valve V_2 and this is communicated to the control grid of valve V_3 which is now cut off, the rise of voltage on its anode being communicated to the control grid of valve V_4 so causing this valve to conduct and the multivibrator has "flipped" to its other stable state. Due to this action the valve V_1 is now opened on its suppressor grid due to the rise of potential at the anode of V_3 and the valve V_2 is now cut off on its suppressor grid as well as on its control grid. When the negative pulse (or spike) representing the trailing edge of the particle appears at the control grids of valves V_1 and V_2 , no action takes place since both valves are cut off.

This pulse is however supplied through the pulse selector unit 20 which comprises diode V_5 to the suppressor grid of valve V_4 causing this valve to be cut off on its suppressor grid.

A greater proportion of the emission current of this valve then goes to the screen grid producing a negative pulse which is communicated to the counter to register the presence of the particle.

This action of the suppressor grid in substantially cutting off the anode current of the valve V_4 causes the multivibrator V_3 , V_4 to flop to its other stable state in which V_3 conducts and V_4 is cut off on its control grid but open on its suppressor grid. This is accompanied by the resetting of the valves V_1 and V_2 to their original starting condition. It is to be noted that the diode V_5 is so connected that positive pulses are prevented from reaching the suppressor grid of valve V_4 and only negative going pulses have any effect on this electrode.

When a large particle is encountered by both scanning and guard beams a waveform of the general type shown in Figure 7(b) is produced and the action of the units 19, 20 and 21 with such a signal will now be described.

When the first positive going pulse representing the leading edge of the particle, as seen by one of the beams, appears on the control grids of valves V_1 and V_2 , the circuits operate to the new stable state as already described above in which condition the multivibrator V_3 , V_4 has flipped and valves V_1 and V_2 are both cut off. When the second positive pulse representing the leading edge of the particle, as seen by the other beam, appears on the control grids of valves V_1 and V_2 the valve V_1 conducts since it is open on its suppressor grid, but valve V_2 remains cut off on its suppressor grid. The drop of potential at the anode of valve V_1 causes the valve V_4 to be cut off on its control grid so that the multivibrator resets or flops to its original stable state in which V_3 conducts. When the multivibrator is actuated in this way no negative pulse appears on the screen grid of valve V_4 . The resetting of the multivibrator causes V_1 to be cut off on its suppressor grid and V_2 to be

8
opened on its suppressor grid, both valves remaining cut off on their control grids.

When the first negative going pulse appears, it has no action on valves V_1 and V_2 but it is passed by unit 20 to the suppressor grid of valve V_4 . Since this valve is cut off on its control grid there is no accompanying decrease of screen potential as in the case of the small particle so that no pulse is emitted to the counter.

When the second negative pulse is received there is again no action and both units 19 and 21 are in their original stable state. It will therefore be seen that a count is only effected when a positive going pulse is followed by a negative going pulse produced either by the scanning or the guard beam. Thus each particle is counted twice and the total count must be divided by two to arrive at the number of particles actually scanned. When a mixed signal comprising two adjacent positive pulses is received then no count is made and the switch and switch control units are left in their original operative condition.

For carrying out the third mode of operation above mentioned, the apparatus shown in block schematic form in Figure 8 may be employed. In this arrangement the scanning and double signal producing means are indicated at 16 the signal due to the scanning beam being differentiated as in the preceding embodiment, and only pulses of one polarity permitted to pass to the input of a coincidence switch 22. The differentiating and pulse selecting means are shown at 23 in Figure 8. The signal due to the guard beam, which may be of substantially rectangular form, is also supplied to the coincidence switch and the arrangement is such that when the signal due to the scanning beam is alone present the counter 9 is actuated by a pulse delivered by the coincidence switch. When both signals are present substantially simultaneously the switch is prevented from being operated so that no signal is passed to the counter.

A circuit for providing this mode of operation is shown in Figure 9. The signal due to the main beam, after differentiation, is applied to the anode of diode V_6 , the cathode of which is connected to the control grid of triode valve V_7 which acts as a pulse inverter. Positive-going pulses of the differentiated signal are applied to the control grid of valve V_7 but negative going pulses are prevented from appearing on this grid. Such positive pulses provide at the anode of V_7 negative going pulses which are applied to a bi-stable multivibrator of the same general type shown in Figure 6. This multivibrator comprises a triode valve V_8 and a pentode valve V_9 , the anode of each valve being connected to the control grid of the other in the usual manner. The differentiated incoming signal is also applied to the suppressor grid of valve V_9 and its control grid is connected to a negative H. T. line through a resistor 24, across which is shunted triode valve V_{10} . The anode of V_{10} is therefore coupled to the control grid of V_9 and has its cathode connected to the negative H. T. line. The signal due to the guard beam is applied to the control grid of V_{10} .

The method of operation of this embodiment is as follows:

Initially the valve V_8 is conducting and the valve V_9 is cut off on its control grid and valve V_{10} is non-conducting due to the connection of its control grid to a negative bias line designated $-HT_2$ in Figure 9.

Considering first the operation with a small particle, the positive-going pulse representing the leading edge of the particle traverses valve V_6 and causes V_7 to conduct so that a negative pulse from the anode of this valve is passed to the control grid of valve V_8 . Valve V_8 is thereby cut off and the multivibrator flips to its other stable state in which V_9 is conducting being open both on its control grid and its suppressor grid. When the negative pulse representing the trailing edge of the particle appears it cannot effect the control grid of V_7 due to rectifier V_6 but it appears on the suppressor grid of

valve V_9 limiting the current to the anode, which causes the multivibrator to flop to its initial stable state. Substantially the whole of the emission current of the valve momentarily goes to the screen grid, the potential of which exhibits a negative pulse which passes to the 5 counter.

When a large particle is encountered by both beams and assuming that the guard beam encounters the particle before the scanning beam, then the control grid of valve V_{10} will go positive (assuming a positive-going pulse) so that V_{10} fully conducts and reduces the potential of the control grid of V_9 . When the positive pulse of the differentiated signal due to the scanning beam is applied to the valve V_7 and the corresponding negative going pulse is applied to valve V_8 the multivibrator cannot flop since the control grid of valve V_9 is being forceably held at a very low potential. Thus when the negative-going pulse of the scanning beam signal is applied to the suppressor grid of valve V_9 no signal appears on the screen grid and thus no count is registered.

In Figure 10 are shown (in pairs) the waveforms of the signals due to the scanning beam and the guard beam respectively for various types of particles. The scanning and counting of a small particle takes place when the waveforms shown at (a) are applied to the coincidence switch. The waveforms at (b) are produced when a long substantially parallel sided particle, sloping in the direction of line scan, is scanned by both beams, and at (c) when such a particle slopes in the opposite direction. At (d) and (e) are shown the waveforms produced when a particle having tapering sides is scanned by both beams, in the first case the sides are convergent in the direction of frame scan and in the second case divergent in the same direction.

At (f) the guard beam alone produces a signal and in each of these cases (b to f) no signal reached the counter since the guard beam has either prevented the multivibrator being set or has returned it, to the condition in which it is non-responsive to the counting signal represented by the trailing negative-going pulse of the differentiated signal due to the scanning beam.

In the preceding description specific reference has only been made to flying spot scanning means of the cathode ray tube type with spot-wobbling means for producing and distinguishing the signals due to the two beams. It will be clear that the same result may be obtained by utilising a flying spot light beam produced by a flying spot scanner of the cathode ray tube type or by a light source and mirror drum or drums, or equivalent optical elements, the beam being divided by any suitable optical element or elements. The two beams thus produced can be given distinguishably different optical properties by being differently polarised or of different colour and two photocells are then employed each responsive to one of the beams only.

One example of such an arrangement is shown diagrammatically in Figure 11 in which a light source 25 in conjunction with a condenser lens or lens system 26 illuminates a double-hole diaphragm 27. Colour filters 28 and 29 which may be respectively red and blue are placed over each hole and an objective lens or lens system 30 projects the images of the two spots of coloured light into a scanning unit 31 which may be for example of the well-known mirror drum type. The emergent raster-producing beams are caused to scan the sample 32, the transmitted (or reflected) light being picked up by one or other of the photocells 33, 34. Each cell may be inherently responsive to only one of the colours and/or colour filters 28a, 29a may be employed to ensure that one cell only sees the red beam and the other only the blue beam. If the particles are of such colour or colours that normal colour filters cannot be used with success, interference type filters may be employed to distinguish the two beams.

In another alternative the raster-producing light beams,

however, initially produced, may be distinguished by being differently polarised that is to say they may be plane polarised at an angle to one another or differently circularly polarised, the photocells each being made sensitive to one of the beams only. Such means are well-known and do not need further description.

In Figure 12 is illustrated diagrammatically another arrangement which comprises a flying spot scanner 35 of the cathode ray tube type providing a raster produced by a single electron beam in the normal manner.

The double scanning beams for scanning the sample are produced by a split lens system 36 one (or both) halves of the system being adjustable to enable the mutual separation of the beams to be accurately determined.

As previously indicated the beams may be distinguished by being differently coloured or of different polarisation, colour filters or polarising elements generally indicated at 37, 38 being disposed in the path of the beams between 20 the lens system 36 and the sample, corresponding filters or polarising elements 37a, 38a being disposed in front of each photocell pick-up 39, 40. The two separate electrical signals may then be employed as hereinbefore described to provide a total count of the number of particles in the sample.

In yet another alternative form diagrammatically illustrated in Figure 13 the sample suitably prepared is scanned directly by an electron beam. The drawing shows diagrammatically a scanning electron microscope 30 of the known type, having a cathode 41, and an anode 42 provided with aperture 43. The anode may therefore be considered as the source of a beam of electrons which is focussed on the image plane 44 by an electron lens or lens system 45. The electron beam is deflected 35 by a deflecting system 46 to which the spot-wobbling potentials are supplied so as to produce a double beam raster at the image plane 44. An electron field lens 47 at this plane causes the electrons emergent from the plane to be concentrated on the aperture of an electron 40 reducing lens 48. A reduced image of the raster at the image plane 44 is thus formed at the sample plane 49. The sample 50 is prepared as a thin film of collodion or the like which the electrons can penetrate and in which the film is opaque to electrons in areas 45 corresponding to the particles. As the sample is scanned by the electron beams the potential of a collector anode 51 will vary depending on the presence or absence of the electron beams and this varying potential can be employed as hereinbefore described to obtain a count 50 of the total number of particles. With such an arrangement it is possible to obtain a count of particles which are smaller than those which can be resolved by an optical microscope and this may have important uses in, for example the biological field.

55 It will therefore be understood that the invention may be employed for counting particles of any kind having a random distribution on a surface and may be used, for example, for counting bacteria or finely comminuted materials of any kind provided they are suitably presented 60 for the particular form of scanning used.

What we claim is:

1. Particle counting apparatus comprising scanning means for providing effectively two scanning beams simultaneously scanning adjacent paths of a sample of the particles to be counted, pick-up means cooperating with said scanning means for producing an electrical signal which is a measure of the presence and distribution of the particles, counting means coupled to said pick-up means and responsive to the derived signal for giving 65 an indication of the total number of particles scanned, and means rendering said counting means inoperative when both beams encounter a particle substantially simultaneously but actuating said counting means when only one of said beams encounters a particle whereby multiple 70 counting of large particles is avoided.

2. Apparatus as set forth in claim 1 wherein said scanning means for providing effectively two scanning beams includes means for providing a main scanning beam and means for providing a guard beam, and means for maintaining a predetermined relative positioning between said beams to cause said guard beam to scan along a line adjacent to the line scanned by the scanning beam and in advance of it by a predetermined distance in a direction parallel to the line scanned by said main scanning beam.

3. Apparatus as set forth in claim 1 wherein said scanning means comprises a flying spot scanner of the cathode-ray tube type and further including spot wobbling means coupled to said scanner for repetitively deflecting the electron beam in a predetermined direction at a repetition frequency greater than the line frequency for producing effectively two scanning beams.

4. Apparatus as set forth in claim 1 wherein said scanning means provides a flying spot beam and further including beam dividing and differentiating means for producing two scanning beams having distinguishably different optical properties, said pick-up means comprising two photo-electric devices each responsive to only one of said scanning beams.

5. Apparatus as set forth in claim 4 wherein said scanning means is a flying spot scanner of the cathode-ray tube type.

6. Apparatus as set forth in claim 4 wherein said scanning means includes a light source and a mirror drum.

7. Apparatus as set forth in claim 4 wherein said beam dividing means comprises a double-hole diaphragm and a lens system.

8. Apparatus as set forth in claim 4 wherein said beam dividing means comprises a split lens system.

9. Apparatus as set forth in claim 4 wherein said beam differentiating means comprises color filters, said photo-electric devices being correspondingly color sensitive.

10. Apparatus as set forth in claim 4 wherein said beam differentiating means comprises polarizing means, said photo-sensitive devices being correspondingly polarization sensitive.

11. Apparatus as set forth in claim 3 further including an amplifier coupled at one end to said counting means and switching means interposed between the other end of said amplifier and said pick-up means, and wherein one of said two scanning beams is a main scanning beam and the other beam is a guard beam and

wherein said spot wobbling means comprises an oscillator generating an alternating potential of substantially square waveform, said alternating potential being applied to said switch means, the arrangement being such that a signal generated by the pick-up means due to the main scanning beam is passed to one input of said amplifier and that due to the guard beam to another input of said amplifier whereby when both signals are present substantially simultaneously one cancels the other so that there is no output signal from said amplifier to said counting means.

12. Apparatus as set forth in claim 2 further including means for electrically differentiating and mixing electrical signals derived from said main scanning beam and said guard beam, a switch control and count pulse generator means coupled to the input of said counting means, a switch unit interposed between said differentiating and mixing means and said control and generator means, and pulse selector means coupled between said differentiating and mixing means and said control and generator means.

13. Apparatus as set forth in claim 2 further including means for differentiating the signal derived from said main scanning beam and a coincidence switch unit interposed between said differentiating means and said counting means, the signal from said guard beam being applied as a pulse of substantially rectangular form to an input of said switch unit.

14. Apparatus as set forth in claim 1 wherein said scanning means comprises an electron microscope having a source of an electron beam adapted to scan said sample and wherein the sample is opaque to electrons only in areas corresponding to the particles, said pick-up means being a collector anode positioned on the opposite side of the sample with respect to said source of the electron beam.
